UNITED STATES PATENT OFFICE

FREDERICK L. FULLER, OF WEST ORANGE, NEW JERSEY, ASSIGNOR, BY MESNE ASSIGNMENTS, TO THE NATIONAL CASH REGISTER COMPANY, OF DAYTON, OHIO, A CORPORATION OF MARYLAND

CASH REGISTER

Original application filed March 20, 1919, Serial No. 283,720. Divided and this application filed June 24, 1927. Serial No. 201,156.

This invention relates to improvements in cash registers and has for its object the provision of an improved indicating mechanism for machines of this class.

5 The machine which is taken for the purpose of illustration only is of the type shown in the application for United States patent filed November 19, 1918, Ser. No. 263,125 in the name of Frederick L. Fuller, but the present invention may, however, be embodied in machines resembling or differing greatly from that shown in said application. The Fuller application has matured into Patent 1,742,701, January 7, 1930.

10 This application constitutes a division of the inventor's application Serial No. 283,720 filed Mar. 20, 1919 and issued September 24, 1929 as Patent 1,729,338, to which reference may be had for further information 15 regarding devices not shown in detail or claimed herein.

15 The main object of this invention is to provide a rotatable indicator which is differentially operable to one of a certain number of positions by the operation of one or more of a smaller number of keys.

20 A more specific object is the provision of a rotatable indicator movable to one of four positions by the actuation of one or two of three keys.

25 The invention has been illustrated in its preferred embodiment in the accompanying drawings, wherein:

Fig. 1 is a vertical sectional view of the 30 illustrative machine looking toward the right and taken just to the right of the left side frame, certain parts having been omitted.

Fig. 2 is a detail of the cam provided for 35 effecting a movement of the indicator supporting bar.

Fig. 3 is a partial rear view of the machine showing the rotatable transaction indicators and the control means therefor.

Fig. 4 is a view in side elevation showing 40 the adjustment of the indicator controlling devices when certain keys are depressed.

Fig. 5 is a side elevation similar to Fig. 4 showing the indicators in a lowered and adjusted position.

50 In the drawings, the numeral 10 indicates

the drawer base usually provided in machines of this kind, upon which is mounted a suitable metal base 11, which serves as a support for the two vertical side frames 12, one of which only is shown in Fig. 1. The mechanism of the machine is enclosed by a suitable cabinet 14, provided with glass windows 15 through which the indicators are visible. 16 indicates the key shaft which extends transversely through the machine and is supported at its ends in the side frames 12. 17 is the revolution shaft common in machines of this character supported in bearings in the side frames 12 and provided with the necessary cams and other means for actuating and controlling the various operations of the machine. These have not been illustrated as they are well known in the art.

The invention has been embodied in the present instance in a machine having thirty-one manipulative devices such as keys, comprising a plurality of banks of amount keys 18, two transaction keys 19_N and 19_P, and one or two auxiliary or clerks' keys 20_A and 20_B.

As is common in machines of this kind 75 there has been provided a key coupler 21 overlying the keys and oscillatable about the pivots 22 journaled in the side frames. The coupler is provided with a nose or flange 23 along its entire length.

In machines of this kind it is generally recognized desirable to be able to successively partially depress the selected keys whereby they become attached to the common member such as a coupler and will be fully operated 85 by said common member upon the depression of any of the selected keys. One means for performing the above function may comprise the form described in the parent application Serial No. 283,720 and as shown in the above-mentioned application may comprise a series of spring-pressed bars 24 one for each group of amount and transaction keys and overlying the rear ends of the same. The bars are preferably pivoted to suitable supports 25 rigidly 90 carried by the coupler and are spring-pressed rearwardly by springs 26. This precise arrangement forms no part of the present invention and is fully disclosed in the parent application above referred to.

Referring to Fig. 1 the revolution shaft 17 is rotated 360° at each operation of the machine by a rack plate 27 provided with rack teeth 28 meshing at selected times with a pinion 29 fixed to the shaft 17. To prevent retrograde motion and therefore insure a full operation of the machine, the shaft 17 is provided also with a ratchet wheel 30 against which bears a pawl 31 pivoted to the side frame 12 at 32 and held thereagainst by a suitable spring 33. At the down-stroke of the key the rear rack teeth engage the pinion 29 and rotate it 180° and at the end of this stroke the rack plate 27 engages a spring-pressed shelf 34 and is thereby forced rearwardly so that the forward rack teeth engage the pinion 29 and cause it to turn the shaft 17 the remaining 180°. The shelf 34 is pivoted as at 35 and held in normal position against the stop 36 by a spring 37. These parts have not been described in detail as they are well known in the art.

It is considered desirable to provide means whereby either of the clerk's keys 20_A or 20_B 25 may partially elevate the key coupler to such a position that the transaction and amount keys may be successively coupled thereto. As best shown in Fig. 1 each of the clerk's keys is provided with a coupler lifting cam edge 38 30 engaging a face 39 of a shoulder of the key coupler 21. When a clerk's key is partially depressed a considerable movement of the key will effect a relatively small movement of the coupler which results in a very easy operation 35 of said key. As the coupler and keys have different centers the point of contact 38 and 39 gradually shifts the coupler from the normal position shown in Fig. 1 to a partially elevated position and this initial movement 40 of the coupler is positively terminated by the engagement of a face 40 of a notch 41 formed in the clerk's key with the flange 23 of the key coupler 21. The key coupler is held in its partially elevated position by reason of the 45 fact that the full-stroke pawl 31 will engage one of the teeth of the ratchet wheel 30.

The transaction and amount keys may now be initially depressed which operation attaches them to the partially elevated key 50 coupler, it being noted that when the coupler is partially elevated the spring-pressed bars 24 will be slightly above the square notches 42 formed in the rear ends of each of the amount and transaction keys. When a transaction or amount key is initially depressed, 55 the associated bar 24 will be urged by the spring 26 rearwardly to engage the notch 42 of the initially operated key thereby positively attaching the key to the key coupler. 60 When the necessary amount and transaction keys have been attached to the key coupler full depression of one of such keys will cause the completion of the upward stroke of the key coupler to perform the usual functions. 65 The above mechanism is not shown or de-

scribed in detail since it comprises no part of the present invention and for a more complete showing and description reference may be had to the parent application Serial No. 283,720, filed March 20, 1919.

70

Transaction indicators

The improved indicator devices preferably comprise two transverse, rotatable bars arranged to provide for a front and back indication. While the indicators may be provided with any desired number of faces in this particular instance they are formed with four faces, each bearing one of the following indications "A-Cash", "B-Cash", "A-Paid out" or "B-Paid out". It will be seen that in this case each of these indications is composed of two indicia, the letter signifying the clerk and corresponding to the series of clerks' keys 20_A or 20_B and the word signifying the type of transaction such as "Cash", which is a normal operation, or a "Paid out" transaction which requires the depression of the key 19_P. The mechanism for disposing the proper face in visible position and therefore displaying the proper indication, is placed under the control of a key of two series (clerk's and transaction).

This mechanism comprises two vertical slides 43 and 44, located on opposite sides of the machine slidably mounted in the rear framework 45 and formed with forwardly extending tails 46 resting on the key coupler 21 (see Fig. 1). These slides are lifted by the coupler at each operation of the machine. In order to insure simultaneous movement of the slides 43 and 44 and, therefore, prevent wedging of the parts, there is provided a shaft 47 journaled in the rear framework 45 and having a pair of pinions 48 at its opposite ends co-operating with rack teeth 49 on the forward edges of the slides 43 and 44. The slide 43 is provided with a nose 50 forming a stop for a purpose to be described later. The upper end of each slide is bifurcated to provide a pair of arms 51. Two rotatable indicator bars 52 and 53 are supported by suitable shafts 54 in bearings in the arms 51. Each shaft 54 at the end adjacent the slide 43 carries a pinion 55 in continuous engagement with a gear sector 56 loosely pivoted on the slide 43. It is obvious that in order to display any desired indication, at both the front and back of the machine, it will be merely necessary to properly position the gear sector 56.

The means provided for this purpose will now be described. Adjacent the slide 43 there are provided three vertically movable slides 57_P, 57_B, and 57_{BP} which come into operation to position the bars to display the indications "A-Paid out", "B-Cash" and "B-Paid out" respectively. Said slides are provided with rearwardly extending shelves 58_P, 58_B and 58_{BP} respectively, normally lo-

cated at substantially the same height. These slides are each provided with tongues 59 for holding said slides in lifted position by engagement with the top edge of a back rod 60

- 5 suitably controlled by a link 61 whose movement is controlled by a cam 62 (Fig. 2) driven by the shaft 17. When released by the back rod these slides are started down by gravity or if they should stick in their guides
- 10 by the action of a spring-urged bail 63 on said tongues.

The gear sector 56 has a pin 64 extending toward the left (Fig. 3) and overlying the shelves and is provided on the right (Fig. 3)

- 15 with another pin 65 which serves as an attaching means for a spring 66 but extends further for engagement with the stop 50.

The lower end of the slide 57_B is bent so as to overlie the rear of the clerk's key 20_B while the lower end of the slide 57_P is arranged to overlie the "Paid out" key 19_P so that said slides may be lifted upon the actuation of their related keys. The third slide 57_{BP} comes into play when each of said keys 20_B and 19_P

- 20 are operated and for this purpose is provided with a pivoted hanger 67. If either one of the keys 19_P or 20_B are operated separately, they will move said hanger 67 sideways and not lift the slide 57_{BP}. When both are operated, however, the slide 57_{BP} is lifted. As is clear from Fig. 3, the tongues 59 are located at different elevations and on account of the varying lengths of the slides they are elevated to and held in different positions so that their respective shelves form variably located stops for determining the position of the gear sector 56 and, therefore, of the indicator bars.

Operation

- 40 If a clerk A makes a cash transaction, he actuates only the key 20_A in connection with amount keys. During the operation of the machine, the slides 43 and 44 and their attached parts are lifted by the key coupler so that the indicator bars are correspondingly elevated. When the coupler drops, the slides and their attached parts descend and the parts come to rest with the pin 65 on the stop 50, it being understood that during this operation the slides 57_B, 57_P or 57_{BP} are not raised. The indicator bars 52 and 53 will now expose the words "A-Cash" on the front and back of the machine. When the machine is operated by the clerk B to register a "Paid out" transaction, the depression of the keys raises the coupler and therewith the slides 43, 44 and their attached parts as in the previous instance. The "Paid out" key 19_P has, however, lifted the slide 57_P and the B key has lifted the slide 57_B and the two keys together, through the agency of the hanger 67, have lifted the slide 57_{BP}. Their respective supporting tongues 59 have been caught and held by the back rod 60, leaving
- 45 the three slides in raised position. The shelf
- 50
- 55
- 60
- 65

58_{BP} of slide 57_{BP} is, however, in the highest position (see Fig. 4) and upon the descent of the indicator parts, serves as a stop for the pin 64 thereby causing the turning of the gear sector 56 from the position shown in Fig. 4 to the position shown in Fig. 5 thereby turning the bars 52 and 53 to expose the words "B-Paid out" at the front and rear of the machine.

Assuming a cash operation of the machine by the clerk B, the slide 57_B will alone be raised whereupon the shelf 58_B forms a stop for positioning the indicator bars to expose the words "B-Cash". Likewise, a "Paid out" operation by the clerk A will result in the lifting of the slide 57_P and the positioning of the shelf 58_P in the path of the pin 64 which will cause the gear sector 56 to turn to adjust the bars 52 and 53 at a position exposing the words "A-Paid out". It will be seen, therefore, there is provided an indicator which is differentially movable to one of four positions by the operation of one or two of three keys.

While the form of mechanism herein shown and described is admirably adapted to fulfill the objects primarily stated, it is to be understood that it is not intended to confine the invention to the one form of embodiment herein disclosed, for it is susceptible of embodiment in various forms, all coming within the scope of the claims which follow:

What is claimed is:

1. In a cash register, clerk's and transaction keys, a one-piece indicator bearing both clerk's and transaction indicia, and means for controlling said indicator by a clerk's key or a transaction key or by simultaneous operation of both, to expose the proper indication.

2. In a cash register, a clerk's key, a transaction key, an indicator, controlling slides overlying said keys and operable thereby, a third slide mounted above and between said slides, and a hanger pivoted thereto and co-operable with both of said keys for operating the third slide when both of said keys are operated.

3. In a cash register, three indicator slides, spaced apart, keys engageable with the two extreme slides, a hanger pivoted to the middle slide and engageable with both keys, whereby the middle slide is operated when both keys are operated, and an indicator common to said slides and movable differentially thereby.

4. In a cash register, three indicator slides, spaced apart, keys engageable with the two extreme slides, means carried by the middle slide and engageable with both keys, whereby the middle slide is operated when both keys are operated, and a rotatable indicator adapted to be moved by said slides.

5. In a cash register, keys, an indicator slide, means on said slide engageable with

two keys for effecting operation of said slide when said two keys are operated simultaneously, said means being movable to ineffective position when only one key is operated, and 5 an indicator movable differentially by said slides.

6. In a cash register, two groups of keys, a one-piece indicator bearing a plurality of indications, each of which is composed of two indicia, corresponding, respectively, to the two groups of keys, and means for controlling said indicator by a key of either group or by simultaneous depression of a key in each group to expose the corresponding indication.

7. In a cash register, a plurality of groups of keys, a one-piece indicator bearing a plurality of indications, each of which is composed of indicia, corresponding, respectively, to the plurality of groups of keys, and means for controlling said indicator by a key of one group or by simultaneous depression of a key in each of said groups to expose the corresponding indication.

25 8. In a cash register, two groups of keys, a one piece indicator differentially movable to expose one of a plurality of indications at a given point, each of said indications being composed of two indicia, corresponding in character, respectively, to the two groups of keys, and means for differentially moving said indicator to expose the proper indication, said means being controlled by a key of either group or by simultaneous operation of a key in each group.

40 9. In a cash register, two groups of keys, a one piece indicator bearing a plurality of indications, each of which is composed of two indicia, means whereby any one of the keys of one group may be coupled with one of the keys of the second group and means for controlling said indicator by said keys.

45 10. In a cash register, a plurality of groups of keys, a one piece indicator bearing a plurality of indications each of which is composed of a plurality of indicia, corresponding respectively, to the keys of one group and a key in another group, means whereby any one of the keys of one group may be coupled 50 with one of the keys of the second group, and means for controlling said indicator by said keys.

55 11. In a cash register, two groups of keys, a key coupler for uniting keys of both groups, a one piece indicator differentially movable to expose one of a plurality of indications at a given point, each of said indications being composed of a plurality of indicia corresponding in character, respectively, to the keys depressed, and means for differentially moving said indicator to expose the proper indication, said means being controlled by said keys.

60 12. In a cash register, an indicator for selectively exposing one of a plurality of indications, keys operable singly controlling

said indicator to expose an indication corresponding to the respective key and another key operable simultaneously with any one of said first mentioned keys for operating said indicator to expose an indication corresponding to the keys operated.

70 13. In a cash register, manipulative totalizer selecting devices, an indicator controllable thereby to indicate the totalizer selected, manipulative totalizer controlling device and means associated therewith for controlling said indicator simultaneously with a totalizer selecting device.

75 14. In a cash register, clerk's keys, an indicator controllable thereby to indicate the key operated, a transaction key and means associated therewith for controlling said indicator simultaneously with a clerk's key to present an indication corresponding to the keys operated.

80 15. In a cash register, the combination of a plurality of keys, an indicator differentially movable to different indicating positions, means whereby said indicator may be moved to different positions by selective operations singly of certain of the keys, and to other positions only by simultaneous operation of said keys in certain combinations, said indicator in each position displaying indicia identifying each of the keys operated.

85 16. In a cash register, the combination with clerks' and transaction keys, of an indicator adjustable to different positions, each position corresponding invariably with a particular key or combination of keys and means requiring simultaneous operation of a certain clerk's key and transaction key to effect adjustment of said indicator to one of its positions.

90 17. In a cash register, a plurality of keys, an indicator, means whereby each of said keys determines a corresponding position of said indicator, and means depending upon a simultaneous depression to determine an additional position of said indicator, said indicator bearing indicia identifying each of said keys.

95 18. In a cash register, a rotatable indicator, a plurality of keys, an element for determining a position of said indicator, and means associated with said element for necessitating a simultaneous operation of said keys to operate the element.

100 19. In combination, a plurality of keys, a rotatable element controlled by the keys and having a plurality of stop positions, each of which corresponds invariably to one particular key or to a particular combination of keys, means controlled by the operation of one key for moving the rotatable element to one of its stop positions, and means requiring the simultaneous operation of more than one key for moving the rotatable element to another stop position.

105 20. A machine as defined in claim 19 in

which the rotatable element is provided with indicia to identify the particular key or combination of keys selected.

21. In combination, a rotatable element having a plurality of selectable stop positions, keys for selecting said positions, one of said positions corresponding invariably to a particular combination of two selected keys, a key operated slide for controlling the rotation of the element to its last named position, said slide having a hanger pivoted thereto and overlying said two keys, whereby said slide is operated only when said two keys are depressed simultaneously.
